D. PEPPER.
ELECTRIC HAND LAMP.
FILED AUG. 15, 1921.

Inventor
David Pepper

by Francis J. Chamberlain
his Attorney.

UNITED STATES PATENT OFFICE.

DAVID PEPPER, OF PHILADELPHIA, PENNSYLVANIA.

ELECTRIC HAND LAMP.

Application filed August 15, 1921. Serial No. 492,281.

To all whom it may concern:

Be it known that I, DAVID PEPPER, citizen of the United States of America, and resident of the city and county of Philadelphia, in the State of Pennsylvania, have invented certain new and useful Improvements in Electric Hand Lamps, of which the following is a true and exact description, reference being had to the accompanying drawings, which form a part thereof.

My invention relates to electric lamps of the hand lamp or flashlight type and has for its object to provide a lamp of this kind of exceedingly simple and effective construction particularly with relation to the switch mechanism by which the battery is connected and disconnected from the lamp. Another object of my invention is to provide in a convenient and secure place in the casing a reservoir for extra lamps and the third object is to provide simple and effective means for changing the focus of the reflector with reference to the lamp.

The nature of my improvements will be best understood as described in connection with the drawings in which they are illustrated and in which—

Figure 1 is a sectional elevation of a hand lamp provided with my improvements.

Figure 2 is a sectional elevation of the upper part of the lamp taken on the line 2—2 of Fig. 1.

Figure 3 is a section on the line 3—3 of Fig. 1 looking upward.

Figure 4 is a section on the line 4—4 of Fig. 1 looking upward, and

Figure 5 is a sectional elevation of the upper part of the lamp, showing certain modifications.

A indicates the lamp casing which, as shown, is formed with a threaded lower end A' and a threaded upper end A². Through the upper part of the casing are formed rectangular openings A³ A³ for the

passage of the switch actuating bar. B is a screw cap closing the lower end of the casing and supporting the spiral spring indicated at C. D D are battery elements having, as shown, contact extensions D' D'.

E is a flared end piece having a threaded portion E' by means of which it screws on the outside of the threaded portion A² of the casing and having at its upper end a threaded portion E² on which screws the cap piece F having an inwardly turned flange F' the function of which is to grip the re-

flector and the lens, not shown, against the upper end of the cap piece E. G is the reflector having a flange G' which rests on the top of the cap piece E, as shown, and having at its base the circular recess G through which the lamp can be passed. H is a lamp holder having an upwardly extending threaded flange H' which screws into the threaded portion A² of the casing. This lamp holding disc is also formed with a downwardly extending threaded flange H² into which screws the socket L' of the lamp indicated at L. I is a disc of insulating material which, as shown in Figs. 1 and 2, is secured to the lamp holder by a nut J and from which depend clips indicated at K K adapted to hold in place spare lamps, as best shown in Fig. 3. M is a plate of insulating material secured on the inside of the casing and M' a covering plate of insulating material; both plates have rectangular openings formed through them in registry with the opening A³ on one side of the casing and between them is clamped the metallic plate N, having extending from its upper end the spring contact tongue N', the end of which is bent so as to form an angle N² with an upwardly extending arm N³ which, when forced upward, comes in contact with the lamp base. From the lower end of the plate N extends the spring contact arm N⁴, the end N⁵ of which rests in contact with the sliding bar indicated at O. This bar extends through the casing as shown and is formed on its upper surface with the angular recess O' which is adapted to receive the angular portion N² of the contact spring when the bar is in the position shown in Fig. 1. The bar is also preferably formed with a transverse detent groove O³ on its upper face, and with a transverse groove O² on its lower face on which rests the end N⁵ of the contact spring N⁴.

The construction I have described involves also the provision below the lamp holder and the top of the upper battery D of a chamber AA which serves as a reservoir for spare lamps.

In the construction shown in Fig. 5 the lamp L has its socket L' screwing into a threaded flange formed at the bottom of the reflector, here indicated at g, said reflector being formed with a flange g' which rests directly on the top of the casing, here indicated at a, and is held in place by a flange

of a screw link f which screws on the outside of the threaded end a^2 of the casing. In this construction the insulated spare lamp holder I is shown as screwing on the 5 threaded flange of the reflector which is indicated at g^3 ; in other respects the construction here shown is similar to that of the other figures.

Referring to the construction of Figs. 1 10 to 4, the lamp holder is secured in the end of the casing by screwing into the threaded end thereof, the lamp screws into the socket of the holder as shown, and the insulated disc I is secured on the under side of the 15 lamp holder as described and spare lamps inserted in the clips K find ample room in the chamber AA one lamp being held on each side of the sliding bar O, as is best shown in Fig. 3. The adjustable head E is 20 screwed on the outside of the casing end and the reflector G and the lens, not shown, are secured in place by the flanged ring F and obviously by screwing the holder E in or out the focus of the reflector with reference 25 to the lamp can be adjusted at will.

The contact springs, formed as described, are secured to the side of the casing and the sliding bar O inserted until its detent slot O^2 is engaged by the end N^4 of the spring 30 arm N^4 . The insertion of this bar at first forces the spring arm N^4 up into contact with the lamp base, but when fully inserted in the position shown in Fig. 1 the detent O^2 permits the spring arm to move downward 35 to the position shown and out of contact with the lamp. Obviously any further movement of the sliding bar O will press the switch up into contact with the lamp.

The spring bar N^4 rests in permanent contact with the contact extension D' of the upper battery as shown and the battery is held in place between this spring and the spring C so as to protect the lamp as a whole from sudden jar which might tend to disrupt or 45 disorder its parts.

Having now described my invention, what I claim as new and desire to secure by Letters Patent, is:

1. In an electric hand lamp means for holding a lamp in position in combination 50 with a contact spring secured to the side of the casing and extending beneath the lamp, said spring having a contact extension by which it is connected to the battery and a sliding bar extending through the wall of the casing, said bar having a recess in its 55 upper face formed to permit the spring contact to recede from the lamp base and break the circuit and also to lock the bar in position, said bar having also a detent in its upper surface adapted to engage with the edge of the hole in the casing to hold the bar in position and being otherwise so formed as to close the circuit when moved.

2. In an electric hand lamp means for 60 holding a lamp in position in combination with a contact spring secured to the side of the casing and extending beneath the lamp, said spring having a spring contact extension by which it is connected to the 65 battery and a sliding bar extending through the wall of the casing and between the contact spring and its battery contact extension, with which the springs are in contact, said sliding bar being so formed that in one position it presses the spring contact against the lamp base and having a detent in its lower face engaged by the end of the lower spring extension to limit the movements of the bar.

3. An electric hand lamp, casing, having a lamp holder at one end, a lamp reservoir chamber lying beneath said holder, and a switch actuating bar, extending transversely 75 through said chamber, the combination 80 therewith of an insulating support and lamp clips secured thereto and extending one on each side of the bar.

DAVID PEPPER.
